UNITED STATES PATENT OFFICE.

JOE M. MCCOMAS, OF KANSAS CITY, MISSOURI.

GRAVE MARKER.

Application filed August 4, 1922. Serial No. 579,621.

To all whom it may concern:

Be it known that I, JOE M. MCCOMAS, a citizen of the United States, residing at 1413 Troost Avenue, Kansas City, in the county 5 of Jackson and State of Missouri, have invented certain new and useful Improvements in Grave Markers; and I do declare the following to be a full, clear, and exact description of the invention, such as will 10 enable others skilled in the art to which it appertains to make and use the same, reference being had to the accompanying drawings, and to the figures of reference marked thereon, which form a part of this specification. 15

My invention relates to grave markers and the principal object thereof is to provide a convenient and durable marker that will be permanent in placement, that will 20 effectively withstand the elements and retain permanently the inscriptions and epitaphs marked thereon.

The invention consists of a preferably metallic plate provided with an extension 25 to form a post or support by which the marker may be secured by an anchoring pin which engages thru the extension to firmly anchor the marker in the ground.

The invention further provides a marker 30 which may be stamped from sheet metal and provided with slots or grooves to receive metallic letters and numerals to build up the required inscription.

It is my intention to supply the marker 35 to dealers in lots and furnish with each lot a font or so of letters so that the dealer may formulate the inscription such as the name of the deceased, date of birth, date of death, and the like to suit the particular 40 need, and in this way, after the letters are inserted on the marker to formulate an inscription, they become a permanent part of the marker and are not subject to the obliteration incident to the use of cards and 45 other markers upon which inscriptions are written.

It is also an object of the invention to provide a marker that is neat in appearance and that may be shaped to meet religious or 50 other requirements.

The specific details of the marker will be apparent by reference to the following description in connection with the accompanying drawing, in which:

Fig. 1 is a perspective view of the marker, illustrating the method of placement.

Fig. 2 is a central vertical sectional view thru the marker.

Fig. 3 is a perspective view of one of the 60 letters used with the marker.

Fig. 4 is a perspective view of one of the letters, illustrating its mounting on the marker.

Fig. 5 is a perspective view of a letter 65 blank to be used in spacing the words in the inscription.

Fig. 6 is a perspective view of the anchoring pin.

Fig. 7 is a modified design of marker, the 70 inscription being contained within the simulation of a cross, and

Fig. 8 is a rear perspective view of a 75 dealer's or undertaker's business card which may be used on the marker if desired.

The marker in its preferred form is 80 stamped from a single sheet of metal to form a plate or inscription-receiving panel 1 of a polygonal shape. The sides 2 and 3 and the top edge 4 thereof, are turned back upon the plate in a roll 5 to form a frame 85 and stiffen the plate as well as enhance the appearance of the marker. The plate or inscription panel carries an extension 6, the side edges 7 and 8 of which are bent back upon the extension to provide a post or support 9 by which the marker may be anchored in the ground. The support 9 is provided with a slot or opening 10 to receive an anchoring pin 11.

The pin 11 is also preferably stamped 90 from a single sheet of metal which is bent back upon itself as at 12 and the opposite ends 13 and 14 are formed at right angles to the portions 15 and 16 respectively to form a T as shown in Fig. 6. The portions 95 15 and 16 of the pin are provided with forwardly extending prongs or teeth 17 and 18 and near the head or T are grooves 19, which are engaged by a tongue or projection 20, struck from the portion 6 at the upper edge 100 of the slot 10.

Substantially midway of the panel 1 is a rectangular depression 21 provided with slots 22, 23 and 24 extending longitudinally thereof to receive the letters 25 to be inserted to form the inscription as shown in 105 Fig. 1.

The letters 25 are embossed on a metal of contrast to the metal in the marker and are formed of a strip approximately the width 110 of the letter, which is doubled back upon itself as at 26 and 27 to the center of the

letter. The ends 28 and 29 are then bent rearwardly of the letter as shown in Fig. 3.

Above and below the inscription may be embossed panels 30 and 31 to carry floral designs or the like, which not only enhance the appearance of the marker, but tend to stiffen and reinforce the inscription panel and permit the use of a relatively thin metal.

At the bottom of the marker, a depression 32 may be provided, having slots 33 for receiving the ears 34 on a plate 35, on which may be embossed or etched the undertaker's or dealer's business card.

As heretofore stated it is my intention to supply the markers in lots to the undertaker and furnish with each lot a font of letters of the type as illustrated. He will then build up the inscription, selecting the letters that suit his need, placing the letters so as to spell the deceased's name in the slot 22, the date of birth in slot 23 and the date of death in slot 24.

In building up the name, for example John Brown, the letter "J" will be selected, the ends 28 and 29 inserted thru the slot 22 and bent over in opposite directions as shown in Fig. 4. The end 28 is preferably shorter than the end 29 so as to permit ready separation of the ends. The letter "O" is next placed and so on until the name is completed, inserting a blank 25 between John and Brown. Whereupon the letters are moved to the center of the slot and additional blanks are placed at the sides thereof to fill up the slot and retain the name in its proper position.

After the inscription is inserted, he may place his card in the position provided and the marker is assembled. The marker is preferably placed before the grave is filled in, as shown in Fig. 1, and the pin or stake 11 extended thru the slot 10 and driven into the ground until the head thereof engages the part 6 of the marker. The tongue 20 then engages one of the grooves 19 and the marker is firmly locked to the stake or pin 11. After the grave is filled in, the extension is firmly anchored and the marker is practically indestructible.

In Fig. 7, I illustrate a modified design of marker in which a cross 36 is stamped in the plate 1 and the inscription is placed

thereon; but in other respects the marker is identical with that illustrated in Figs. 1 and 2.

The marker may be provided with reinforcing ribs 37 and 38 and the whole weather-proofed to make the color thereof permanent.

From the foregoing it will be evident that the marker is simple in construction and easy to manufacture yet it is strong and not easily destroyed and is well adapted for its purpose.

What I claim and desire to secure by Letters-Patent is:

1. In a grave marker, an inscription-bearing plate, an extension of said plate to form a support, having an opening therein, a tongue extending from the support adjacent to the opening, an anchor pin extending thru the opening, having a head thereon for engaging the side of said support, and a groove in the pin to be engaged by said tongue.

2. In a grave marker an inscription bearing panel, a support for the panel and an anchoring pin for engaging the support comprising a bar doubled on itself the opposite ends of the bar being extended at right angles to the body of the pin to form a T-shaped head for the pin.

3. A grave marker comprising a metallic sheet, the edges of which are rolled to form a frame, an extension on the plate to form a ground support, and means for anchoring the support in the ground.

4. In a grave marker a panel comprising a metal stamping, having an extension the edges of which are turned back upon said extension to form a ground post.

5. In a grave marker an inscription-bearing panel having a support, an anchoring pin having a head for engaging one side of said support and means on the other side of the support to engage the anchor pin to lock the support to the pin.

6. In a grave marker an inscription-bearing panel having a support, an anchoring pin having a head for engaging said support and means for adjustably locking the support against the head of said pin.

In testimony whereof I affix my signature.

JOE M. McCOMAS.
